CLAIM

The ornamental design for a corner mounted combined lighting fixture and motion sensor, as shown and described.

DESCRIPTION

FIG. 1 is a front perspective view of a corner mounted combined lighting fixture and motion sensors showing my new design;

FIG. 2 is a front elevational view thereof;

FIG. 3 is a side elevational view thereof, the opposite side being a mirror image;

FIG. 4 is a top plan view thereof;

FIG. 5 is a rear elevational view thereof; and,

FIG. 6 is a bottom plan view thereof.

FIG. 1

FIG. 2

FIG.3

FIG.4

FIG. 5

FIG. 6
